GRINDING MACHINE

Alvin F. Alt and Jacob Decker, Cincinnati, Ohio,
assignors to The Cincinnati Milling Machine
Co., Cincinnati, Ohio, a corporation of Ohio

Application October 7, 1947, Serial No. 778,314

9 Claims. (Cl. 51—165)

1

This invention relates to grinding machines and more particularly to improvements in infeeding mechanisms therefor.

One of the objects of this invention is to provide an improved precision grinding machine which will grind work to very limited tolerances as respects both diameter and roundness.

Another object of this invention is to provide a machine which will have a continuous feeding motion until the desired size of work has been reached and still maintain a high degree of precision with respect to size and roundness of work.

A further object of this invention is to provide an improved automatic size control grinding machine.

Other objects and advantages of the present invention should be readily apparent by reference to the following specification, considered in conjunction with the accompanying drawings forming a part thereof, and it is to be understood that any modifications may be made in the exact structural details there shown and described, within the scope of the appended claims, without departing from or exceeding the spirit of the invention.

In the drawings in which like reference numerals indicate like or similar parts:

Figure 1 is a front view of a machine embodying the principles of this invention.

Figure 2 is a diagram of the hydraulic control circuit of the machine.

Figure 3 is a view showing an enlarged view of one of the valve control mechanisms.

Figure 4 is a detail view of an adjustable trip control plate.

Figure 5 is an elevational view partly in diagrammatic form showing the size control mechanism and connections thereto.

In the grinding of work diameters to a precision dimension by the infeeding method, it is customary to stop the infeeding motion of the grinding wheel at some predetermined point and allow a dwell before the grinding wheel retracts for the purpose of allowing the work to make a few rotations to facilitate rounding up of the work as well as obtaining a predetermined dimension as to size. Without such tarry allowance, it is very difficult to obtain work that is round within desirable tolerances. Many factors cause this result, some of the more important of which are due to the fact that the work has a tendency to spring slightly under the pressure of the wheel and another is that the wheel may not be cutting freely. It should also be obvious, however, that by allowing time for a tarry that it takes longer to grind a given work piece.

2

By means of this invention a feeding cycle for the grinding machine is provided which produces a rapid traverse motion of the grinding wheel until engagement with the work is established, 5 followed by a normal infeeding rate during which most of the stock removal is effected, after which a very slow feed rate predetermined in accordance with the tolerance allowance for roundness is created until an automatic sizing mechanism, 10 which is in engagement with the work, closes a circuit at the moment the work reaches a predetermined size, energization of this circuit causing immediate retraction of the grinding wheel.

15 This invention includes the discovery that by making this slow feed rate a function of the tolerance allowed for roundness of the work that very accurate results may be obtained. In view of this, the mechanism of this invention is so 20 contrived that the lag between the energization of the circuit and the actual retraction of the grinding wheel is a fraction of a second, and is therefore less than the amount of infeed effected in a second; and by making the infeed per second 25 not greater than the tolerance allowed on the work for roundness, it is insured that the overrun after the closing of the sizing control switch will be less than the infeed per second, and therefore less than the tolerance allowed for roundness.

30 Referring to the drawings, Figure 1 shows a machine embodying the principles of this invention and this machine comprises, in general, a bed 10 upon which is slidably mounted a work supporting table 11 having a headstock 12 and a tailstock 13 for supporting a work piece for rotation in the customary manner. As shown in Figure 2, a grinding wheel 14 is rotatably mounted upon a cross slide 15 which is suitably guided on the bed 10 for relative movement toward and from a work piece indicated diagrammatically by the reference numeral 16. A suitable cross feed screw 17 is in threaded engagement with a nut portion 18 of the slide 15 and 35 operatively connected to the hand wheel 19 shown on the front of the bed 10. The hand wheel 19 may be utilized for roughly determining the position of the grinding wheel with respect to the work and may be utilized for effecting compensation in the position of the wheel.

40 In the automatic infeeding cycle the cross feed screw 17 is provided with a piston 20 which is slidably mounted in a cylinder 21 formed integral with the bed 10 whereby the screw 17 is reciprocated axially to effect advance and retraction of the grinding wheel. The piston 20 is

utilized to effect advance of the grinding wheel, and a second piston 22 slidably mounted in a cylinder 23 is connected by a piston rod 24 to the wheel slide 15 for effecting retraction of the grinding wheel.

The cylinder 21 is connected by line 25 to port 26 of a by-pass valve 27, the plunger 28 of this valve having an annular groove 29 which is normally in position to connect port 26 to port 39. The last-named port is connected by channel 31 to port 32 of a servo-control valve 33. Also, the cylinder 23 is connected to the servo-valve by a channel 34 which leads to port 35 of the by-pass valve, the plunger of which has a second annular groove 36 which is in position to connect port 35 to port 37 and channel 38 which leads to port 39 of the servo-valve. The servo-valve has a pressure port 40 which is connected to the delivery line 41 of a pump 42 which has an intake 43 through which fluid is withdrawn from a reservoir 44. The servo-valve also has a pair of exhaust ports 45 and 46 which are connected to the return line 47 which leads to the reservoir 44.

The servo-valve has a slidable bushing 48 mounted therein which is normally urged toward the left as viewed in Figure 2 by a spring 49. This movement is limited by a cam 50. A pivoted bell crank 51 is interposed between the end of the bushing 48 and the cam, one arm of the bell crank being provided with a roller 52 which rides on the cam surface. The servo-valve also has a plunger 53 which is slidable within the bushing and normally urged toward the left by a spring 54. The valve plunger has a socket connection at 55 with the end of a feed back lever 56 and the clockwise movement of this lever is limited by a set screw 57 engaging a fixed abutment 58. The position of the valve plunger 53, as determined by the set screw 57 relative to the position of the bushing 48 as determined by the cam 50 when in its starting position, is such that the valve spool 59 of the valve plunger 53 is to the right of pressure port 40, as viewed in Figure 2, whereby the pressure from the pump will flow through port 39, channel 38, and interconnected channel 34 to cylinder 23 and thereby exert a continuous pressure on the piston 22 to hold the grinding wheel in a retracted position. At this time the line 31 which leads to cylinder 21 will be connected to reservoir through the interconnection of ports 32 and 46 by the annular groove 60 in the valve plunger 53.

The cam 50 is interconnected for rotation by the infeed control lever 61 which, as shown in Figure 3, is pivotally connected at 62 for oscillatory movement in the plane of the drawing, and also for rotary movement about the axis 63. The lever is connected by a link 64 to a slidable valve plunger 65 which is provided with a flange 66 against which a spring 67 acts to hold the valve plunger in the position shown. It will be noted that this valve plunger has an annular groove 68 which, in the position shown, interconnects ports 69 and 70. The port 69 is connected by the branch line 71 to the main reservoir line 47. The port 70 is connected by a channel 72 to a port 73 located in the end of a short circuiting valve 74 shown in Figure 2. The pump supply line 41 has a branch connection 75 to a third port 76 whereby when the control lever 61 is manually pulled to the left as viewed in Figure 3 the pressure port 76 is connected by the annular groove 68 of valve plunger 65 to port 70, thereby admitting pressure to the lower end of the short circuiting valve and

causing the plunger 76' of the valve to shift upward against the resistance of a spring 77.

The purpose of the short circuiting valve 74 is to short circuit or interconnect both ends of an infeed control cylinder 78 which has a piston 79 that is connected to a rack piston rod 80. This rack intermeshes with a pinion 81 which is formed integral with the bushing 82 shown in Figure 3. When the operator starts the cycle of operation he pulls the lever 61 toward him to operate the short circuiting valve so as to short circuit or interconnect opposite ends of the cylinder 78 and then he rotates the lever 61 in a clockwise direction as viewed in Figure 2 from the starting position indicated by the dash and dot line 83 and in so doing he moves the rack piston rod 80 downward and this becomes possible because of the short circuiting of both ends of the cylinder 78. Upon movement of the lever 61 from the position 83 to the position indicated by the dash and dot line 84 the piston 79 has moved down sufficiently to uncover a port 85.

The cylinder 78 also has a port 86 which is connected by channel 87 to port 88 of the short-circuiting valve and when this valve is moved upward, this port is connected by groove 89 in the valve plunger 76' with port 90, and this port is connected by channel 91 to port 85 of cylinder 78.

When the control lever 61 moves from the position 83 to the position 84, it also rotates the cam 50, whereby the angular surface 92 on the cam will cause counterclockwise rotation of the bell crank 51 and shift the servo-valve bushing 48 toward the right a sufficient distance that the pressure port 40 becomes connected to port 32 whereby pressure fluid will flow to cylinder 21, causing rapid advance of the piston 20 and thus rapid infeed of the grinding wheel. This rate of movement will continue until a collar 93 operatively connected for movement with the screw 11 engages the end of the lever 56, causing counterclockwise rotation thereof and movement of the servo-valve plunger 53 toward the right to thereby follow up the movement of the bushing 48, tending to close the pressure port 40.

There is no exact limit upon how far the lever 61 is rotated manually by the operator to effect the rapid movement, and the length of this movement is determined by the operator observing that the grinding wheel has become engaged with the work and has started grinding. At this point the operator releases the lever 61 which is then returned to its normal position by the spring 67 shown in Figure 3, and through valve plunger 68 releases the pressure on the short-circuiting valve because the port 70 is then connected to the exhaust port 69.

When the valve plunger 76' of the short circuiting valve returns to its normal position it connects port 90 with port 94 and port 88 with port 95. The port 94 is supplied with pressure from the pump line 41 through interconnection of ports 96 and 97 by the annular groove 98 in the reversing valve plunger 99 of a reversing valve 100. The port 97 is connected by channel 101 to port 94. It will now be seen that pressure fluid will flow through line 91 to the upper end of cylinder 78 and thereby continue the downward movement of the piston 79, but the movement will now be under power and not manual control. The rate of this movement is controlled in the following manner.

The return fluid flowing through line 87 and interconnected ports 88 and 95 will continue through line 102 and interconnected ports 103

and 104 of the reversing valve 100 to line 105. The line 105 has two branches, 106 and 107. The fluid passing through line 106 goes to a fast feed rate control valve 108 and the fluid flowing through line 107 goes to a slow feed rate control valve 109. The line 106, however, is actually connected to a port 110 of a cut-off valve 111, and this port is connected to port 112 by the annular groove 113 in the valve plunger 114, which plunger is normally maintained in the position shown by a spring 115. The slow feed valve 109 is set for a very slow feed rate, the purpose of which will be explained later, and therefore since it has a higher resistance to flow than the valve 108 most of the fluid will pass through the valve 108 during the normal infeeding movement of the grinding wheel.

During the downward feeding movement of the piston 19, the cam 58 is continuously rotated and continually moving the servo-valve bushing 48 toward the right, which movement is continuously followed up by the feed back connection to the servo-valve plunger 53. Thus, the grinding wheel is moved in under the direct control of the servo-valve which, in turn, is remotely controlled by the rate of movement of the piston 19, this rate of movement being determined by the setting of the rate control valves 108 and 109. At some predetermined point before the work has reached its final size, such as at the position indicated by the line 116 for the control lever 61 in Figure 2, the rate of infeeding movement of the grinding wheel, is automatically changed to a very slow feed rate.

This is accomplished by means of a trip member 117 which is attached by bolts 118 to the periphery 119 of the rotatable member 82. This trip member is adapted to engage a finger 120 secured to a lever 121 which is pivoted at 122 to a fixed part of the machine. The lever 121 has a connection at 123 to the plunger 124 of a pilot valve 125. This pilot valve has a pressure port 126 which is supplied by the pump 42 and when the plunger 124 is moved upward through trip operation the pressure port 126 is connected by the annular groove 127 in the valve plunger to port 128 whereby fluid pressure will flow through line 129 to the lower end of the cut-off valve 111, thereby shifting the plunger 114 upward as viewed in Figure 2. This will disconnect port 110 from port 112 and thereby block further flow to the rate valve 108 whereby all the flow must now pass through line 107 to the slow rate valve 109. This will materially reduce the rate of movement of the infeed control piston 19, and through the various connections to the servo-valve, thereby slowing down the rate of infeed movement of the grinding wheel.

The final size of the work is measured and determined by an electric sizing mechanism which is more particularly shown in Figure 5. From this figure it will be noted that the work piece 16 which is in engagement with the grinding wheel 14 is engaged by two fixed points 130 and 131 which are carried by a semi-circular frame 132 forming part of the frame of the sizing device. A straight arm 133 to which the portion 132 is connected has a reciprocable plunger 134 slidably mounted therein and the lower end of this plunger engages the periphery of the work. The upper end of this arm operates an indicator 135 and also operates a switch contained within the housing 136 which may be adjusted to close when the indicator produces the desired reading. In other words, the member 134 will move downward gradually as the work reduces in diameter until

the switch closes at which time a circuit is energized to operate a solenoid 137. The electric sizing device forms no part of the present invention and may be the same as that shown in United States Letters Patent 2,267,559.

The sizing device is supported by an arm 138 to a pivoted support 139 which is attached at 140 to the grinding wheel housing whereby it may be supported in suitable position for engagement 10 with the work. When the circuit 138' is energized to cause operation of the solenoid 137 the plunger 139' of this solenoid operates through a lever 140' to depress the plunger 28 of the by-pass valve 27. This results in port 26 of the valve being connected to port 141 which is connected to the reservoir line 47 so that the fluid in cylinder 21 can exhaust to reservoir. Port 35 and its line 34 from cylinder 23, is connected to pressure port 142 by the annular groove 36 in valve plunger 28 15 whereby the pump pressure from line 41 may directly enter cylinder 23 to cause immediate retraction of the grinding wheel and independent of the rest of the circuit. The grinding wheel is thus moved out of engagement with the work 20 without waiting for the rest of the circuit to be reset for starting.

The by-pass valve 27 has a second pressure port 143 which is connected by the shifting of the plunger 28 to port 144 by the annular groove 145 so that fluid pressure will now flow through line 146 to port 147 located in the lower end of the reversing valve whereby the reversing valve plunger 99 is immediately shifted upward.

This will result in pressure port 96 being disconnected from port 97 and connected to port 103 whereby the fluid pressure will now flow through line 102 and the short circuiting valve to line 87 and thereby to the lower end of the infeed cylinder 78 to cause upward movement of piston 79. Port 97 of the reversing valve to which the upper end of cylinder 78 is connected will be connected to the exhaust port 148 whereby fluid may discharge from the upper end of the infeed control cylinder.

Thus, as the grinding wheel is being retracted, the manual control lever 61 is being rotated by power back to its starting position, and this movement will continue until a trip pin 149 carried by the rod 80 rotates the lever 121 and shifts the pilot valve downward to its original position. It will be noted that the piston 19 is provided with an interdrilled passage 150 which will register with a port 151 at about the time the port 85 closes so that the fluid in the upper end of the cylinder may still be exhausted to reservoir through the line 152.

When the pilot valve plunger returns to its original position port 128 will become reconnected to an exhaust port 153 which will release the pressure in the lower end of the cut-off valve 111 so that the plunger 114 thereof will be restored to its original position.

Referring to Figure 3, attention is invited to the fact that the rotatable member 82 which is rotated by the handle 61 about the fixed stud 82' has an arcuate groove 154 formed therein and that the fixed member 82' has an interdrilled pressure port 155 and an interdrilled exhaust port 156. Intermediate these ports is a third port 157 which is connected by line 158 to a pressure switch 159. At the beginning of the cycle when the manual control lever 61 is rotated clockwise as viewed in the diagrammatic positions shown in Figure 2 the arcuate groove 154 moves clockwise as viewed in Figure 3 to connect the pres-

sure port 155 with port 157 and thereby close the pressure switch 159. It will be noted that the pressure switch 159 is connected in series in the control circuit 138' for the solenoid 137. Thus, this switch is closed during the entire infeed cycle, but when the lever returns to its starting position the port 157 is connected to the exhaust port 156 which results in the pressure switch 159 opening the circuit 138', thereby releasing the solenoid 137 whereby the valve plunger 28 of the by-pass valve returns to the position shown due to the fact that the back pressure in line 47 entering the port 141 will pass through the inter-drilled passage 160 to the lower chamber 161 of the valve housing and push the plunger back to its normal position. This will result in the line 146 from the lower end of the reversing valve being connected to the return line 161 whereby the spring 162 will shift the reversing valve plunger to its return position.

The operator may now swing the sizing gage out of the way and remove the finished work piece, insert a new work piece between the centers of the machine and then return the sizing device into engagement with the work, but at this time since the work is an unfinished piece, the plunger 134 will be held upward in such position as to hold the switch of the sizing device open so that the circuit to the solenoid 137 will not be energized when the pressure switch 159 is closed at the beginning of the next cycle.

The machine thus has a cycle of operation comprising a rapid traverse stroke of the grinding wheel from its work clearing position into grinding engagement with the work, a feed stroke during which most of the stock is removed from the work, and a short feed stroke at a very slow rate, the last rate being a function of the tolerance allowed on the work for roundness. The sizing device is in continuous engagement with the work during this continuous infeeding motion at the different rates, and when the exact size is reached immediate separation between the grinding wheel and the work is effected.

It will be noted that there is no provision for an intentional dwell, and that reversal in the direction of movement of the grinding wheel is made as instantaneously as possible without waiting for resetting of the various control elements in the control circuit. The use of a dwell is normally for the purpose of rounding up the work but is time-consuming. The object here is to grind within the same minimum tolerances for roundness of the order of .0001" or .0002" without the use of a dwell. By careful experimentation, we have discovered that by making the slow infeed rate per second of time equal to the tolerance allowed for roundness of the work which, in turn, is equal to the rate of stock removal per second which is a function of the feed rate and the rate of rotation of the work, that the desired tolerance may be obtained and with greater surety. In view of this, the slow feed rate valve has been provided and made effective at the proper time at the end of the infeeding stroke to produce the desired feed rate per second which is equal to or less than the tolerance allowed for roundness of the work.

What is claimed is:

1. In a grinding machine having a grinding wheel and a work support, the combination of power operable means for feeding the grinding wheel toward the work support to progressively effect a reduction in the size of work carried by the work support, said power operable means in-

cluding piston and cylinder means for shifting the grinding wheel, a hydraulic control circuit including a reversing valve for controlling the direction of movement of said piston means, a source of pressure, and an additional valve for directly connecting said source of pressure to said piston and cylinder means to effect retraction of said grinding wheel independent of said reversing valve.

10 2. In a grinding machine having a grinding wheel and a work support, the combination of power operable means for shifting the grinding wheel toward the work support to progressively effect reduction in the size of work carried thereby including a servo-motor control mechanism, a hydraulic motor for driving said mechanism, a reversing valve for said motor, a source of pressure for supplying fluid to said motor, and an additional valve for directly connecting said source of pressure to said power operable shifting means to effect immediate retraction of the grinding wheel independent of said mechanism.

15 3. In a grinding machine having a grinding wheel, a grinding wheel support and a work support, the combination with fluid operable means for shifting the grinding wheel support toward the work support to progressively effect reduction in the size of work carried by the work support including a hydraulic control circuit having a source of pressure connected thereto, and valve means for controlling the rate of operation of said power operable means, of an electrical work sizing gage mounted on said grinding wheel support, and valve means connected for operation by said gage for directly connecting said source of pressure to said fluid operable means independent of said first-named valve means for effecting retraction of the grinding wheel support.

20 4. A grinding machine having a work support and a grinding wheel support mounted for relative movement to advance and retract one with respect to the other, means actuated by fluid pressure to effect said advancing relative movement, a source of fluid pressure, and a control mechanism for governing the flow of fluid pressure from said source to said means whereby the rate of flow becomes the sole determinant of the rate of said relative movement, said mechanism including manually operable means for adjusting said flow to a fast rate to effect said relative movement at a rapid traverse rate, a power operable mechanism for reducing said flow to effect said relative movement at a normal grinding rate, a subsequently operable device to further restrict the flow to yield a slow rate per second which is less than the tolerance on the work for roundness, and a sizing device responsive to continuous reduction of the work and effective in response to a predetermined work size during said slow rate to effect immediate separation of said supports.

25 5. A grinding machine having a work support and a grinding wheel support mounted for relative approach and retractive movements one with respect to the other, means actuated by fluid pressure to effect the advancing relative movement, a source of fluid pressure, valve means intervening the source of fluid pressure and said actuatable means for controlling the rate of flow from said source to said actuatable means, cam means for actuating said valve means to vary said rate of fluid flow, manual means operable on said cam means to cause a rapid traverse flow, power operable means effective on said cam means to restrict the flow and thereby produce a normal grinding rate, means actuatable by said

power operable means and operatively effective on said cam means to further restrict the flow to effect a predetermined slow rate of relative movement per second that is less than the tolerance allowed on the work for roundness, a sizing mechanism responsive to the size of the work, and means operable thereby to effect immediate separation of said supports during said slow rate of movement.

6. A grinding machine having a work support and a grinding wheel support mounted for relative movement one with respect to the other, fluid operable means for effecting said relative movement, a source of fluid pressure therefor, and control mechanism for governing the flow of pressure fluid from said source to said means including manually operable means for adjusting said flow to obtain a rapid traverse rate of relative movement, means for restricting the rate of flow to said means to produce a normal grinding rate of relative movement, means subsequently operable by the moving support for automatically effecting a further restriction in the rate of flow to produce a rate of relative movement which is less than the tolerance allowed for roundness of the work, and means dependent on the size of the work and effective during said slow rate of movement to effect immediate separation of said supports whereby any overrun will be less than the tolerance allowed on the work for roundness.

7. A grinding machine having a work support and a grinding wheel support mounted for relative movement one with respect to the other, piston and cylinder means for effecting a relative advancing movement of one of said supports toward the other, a source of fluid pressure, valve means for controlling the rate of flow of fluid pressure to said cylinder means and the flow of fluid from said cylinder means, a control mechanism for actuating said valve means for governing the rate of fluid flow therethrough including manually operable means for adjusting said valve means to obtain a rapid traverse rate of relative movement, means operative upon said valve means for restricting the rate of flow therethrough to produce a normal grinding rate of relative movement, means subsequently operable for effecting a further restriction in the rate of flow to produce a rate of relative movement which is less than the tolerance allowed for roundness of the work, and means dependent on the size of the work and effective during said slow rate of movement and operative upon said piston and cylinder means to effect immediate separation of said supports.

8. In a grinding machine having a grinding

wheel and a work support, the combination of power operable means for feeding the grinding wheel toward the work support to progressively effect retraction in the size of work carried by the work support, said power operable means including piston and cylinder means for shifting the grinding wheel, a hydraulic control circuit including valve means for controlling the rate of said shifting movement, a source of pressure, an electrical sizing gage for continuously measuring the work during the grinding operation, said gage having a switch adapted to be closed upon the work attaining a predetermined size, an electrical circuit in series with said switch and an electrically operable valve in said circuit for actuation by the closing of said switch for directly connecting said source of pressure to said piston and cylinder means to effect retraction of said grinding independent of said valve means.

9. In a grinding machine having a grinding wheel and a work support, the combination of power operable means for feeding the grinding wheel toward the work support to progressively effect a reduction in the size of work carried by the work support, said power operable means including piston and cylinder means for shifting the grinding wheel, a hydraulic control circuit including valve means for controlling the rate of movement of said piston means, trip controlled means effective on said valve means for reducing the rate of movement to a slow rate, a source of pressure, an electrical sizing gage operatively engaged with the work being ground and having a switch adapted to be closed during said slow rate of movement and an electrically operable valve electrically connected to said switch for operation thereby to directly connect said source of pressure to said piston and cylinder means independent of said valve means to effect immediate retraction of the grinding wheel upon the work attaining the gage determined size.
